United States Patent Office

Des. 211,644
Patented July 9, 1968

211,644

MICROPHONE

Hugo Sterkenburg, Eindhoven, Netherlands, assignor to North American Philips Co., Inc.

Filed May 23, 1967, Ser. No. 7,242

Claims priority, application Switzerland Nov. 30, 1966

Term of patent 14 years

(Cl. D26—14)

FIG. 1

FIG. 2

FIG. 1 is a front elevation of the microphone, showing my design;

FIG. 2 is a front elevation of the microphone in a slightly inclined position.

The side opposite to that shown in the drawing is similar in appearance.

I claim:

The ornamental design for a microphone, as shown and described.
